LOOM ATTACHMENT

Linus Sturm, Freehold, N. J., assignor to A. & M.
Karagheusian, Inc., New York, N. Y., a corporation of Delaware

Application October 19, 1934, Serial No. 749,114

27 Claims. (Cl. 139—21)

This invention relates to up-side-down weaving of pile fabrics according to the principles disclosed in the applicant's copending application, Serial No. 698,884, which became U. S. Patent No. 5 2,013,588.

The present invention relates to improvements in the mechanism for holding the severed ends of the pile warps during the intervals in which such pile warps are not being selected and woven 10 into the fabric.

The objects of the present invention are to simplify the construction of the pile-warp holding means, and to provide simple and efficient means for facilitating the cutting of the pile loops.

15 In the accompanying drawings:

Fig. 1 is a longitudinal sectional elevation of sufficient of a loom to illustrate the present invention as applied thereto;

Fig. 2 is an enlarged longitudinal sectional elevation illustrating the manner in which the pile warp ends are held and the pile loops are cut by the mechanism of the present invention; and

Fig. 3 is a fragmentary perspective view illustrating the holding mechanism.

20 In the accompanying drawings, the breast beam of the loom is illustrated at 1. On the upper surface of the breast beam 1 is the breast plate 2. The loom employed is preferably of the "Wilton" type and under normal weaving conditions the underside of the fabric would bear on the upper surface of the breast plate and would pass over the front edge of the breast beam and around the usual spiked take-up roll which is intermittently rotated and maintains 25 the fabric, from the fell to the spike roll, under rather heavy uniform tension, whereby the unwoven warp threads, from the fell of the fabric to the whip rolls or other feeding means at the rear of the loom, are likewise maintained under 30 rather heavy tension.

In the present case, as in the applicant's earlier application above noted, the fabric is reversed, that is, the groundwork of the fabric is uppermost and the pile face of the fabric lies underneath and is hidden from view. In the present case, as in the applicant's earlier application, the binder warps and stuffer warps, are the only ones which at all times are connected to the woven fabric, the pile warps being connected to the fabric only at such times and places as when and where the individual pile warps are called by the pattern mechanism of the loom to form a part or parts of the design being depicted on the pile face of the fabric. The pile warps when 50 called to produce a certain part of a design are

5 passed around the usual form of pile wire and bound into the groundwork or base of the fabric by being passed around and between the weft threads of the fabric base and as the fabric is drawn forwardly by the spike roll the pile warps are similarly drawn forward by reason of there being connected to the fabric as a result of having been selected to form a portion of the design. The pile warps are severed from the fabric adjacent the last pile tufts formed by the respective 10 pile warps and the ends of the pile warps which had been previously severed from the fabric are cut off close to the sole or first pile loop of a series formed by the pile warp as the pile wires are successively withdrawn from the fabric. 15

In the present instance, the rear edge of the breast plate 2 is provided with an upwardly extending flange 3, said flange being beveled and inclined forwardly, as indicated at 4, and reversely beveled and inclined rearwardly, as indicated at 5, which provides a more or less sharp upper edge 6 on the flange 3.

As the fabric is moved forwardly in the manner above described, the pile warps x^1, x^2, x^3, x^4 etc. are drawn over the beveled edge 6 of the flange 20 3 between said edge and those portions x of the pile loops X which lie around and under the pile wires 7, the tension on the fabric and the binder warps y, y and stuffer warps z effecting a gripping 25 of the pile threads x^1 etc. between the holding edge 6 and the underside x of the pile tufts X .

Gripping of the pile warps solely by the edge of the flange and the bottoms of the pile loops is not sufficient to hold the pile warps x^1 etc. in place against the back tension thereon when the 30 pile warps are severed from the fabric. In order to hold the severed pile warps against the above noted back tension, in a position to be worked into the fabric and around the pile wires 7 when selected by the pattern mechanism of the loom, 35 auxiliary holding means 10 is provided. In the present case, this means comprises a plurality of L-shaped elements 11 each having a long leg 12 normally resting against the front surface 13 of the breast plate flange 3, the upper edge of each 40 of said legs being beveled and inclined forwardly, as indicated at 14, providing a relatively sharp thread-gripping edge 15 at the upper end of the L-shaped element 11. Extending at right angles to the leg 12 is the second leg 16 of each L-shaped 45 element 11.

Secured to and projecting below the underside of the substantially horizontal leg 16 of each of the elements 11 is a short stud 17 which is substantially axially aligned with a corresponding 50

short stud 18 which is rigidly mounted in the breast plate 2 and extends substantially vertically from and above the upper surface 19 of said breast plate, each aligned pair of studs 17 and 18 being encircled by a coil spring 20 individual to the short holding elements 11, 11 respectively.

The springs 20 exert a constant upward pressure on the elements 11 forcing the sharp upper edges 15 thereof into firm holding contact with the pile warps, which, after passing over the upper edge 6 of the flange 3, pass over the sharp edges 15 of said elements 11.

As shown in Fig. 3, the holding elements 11 are relatively narrow and are disposed one alongside the other transversely of the loom, from one side of the breast plate 2 to the opposite side thereof, and these elements 11, by reason of their individuality and each having a spring 20, are relatively movable and for this reason may adapt themselves to any variation occurring among the pile warp threads at points intermediate the sides of the fabric being woven.

Paralleling the flange 3 and disposed at an angle to the plane of the breast plate 2 is a second plate 21 which is provided with a rear edge 23. This rear edge of the plate 21 converges slightly toward the rear face 13 of the flange 3, providing an operating slot 24 for the vertical legs 12 of the warp-holding elements 11, whereby forward movement of the elements 11 is limited by the wall 23 of the slot 24 and rearward movement of said elements is limited by the front face 13 of the flange 3 forming the second wall of the slot 24, vertical movement of said elements, however, under the influence of the springs 20, being restricted only by the fabric and warp ends passing over the upper edges 15 of the elements 11.

Mounted on the upper surface of the supplementary plate 21 is an anvil block 25, the rear edge 26 of which is inclined forwardly to be engaged by the forward legs x⁵ of the pile loops X as the pile wires 7 with the respective courses of pile loop X thereon are successively moved forwardly by the corresponding movement of the fabric as a whole, prior to the foremost course of pile loops, i. e. the course passing around the foremost pile wire 7a, being cut as the pile wire 7a is withdrawn from the fabric.

Formed in the upper surface 21 of the plate 21 is a groove 28, the rear wall 29 of which is disposed in an inclined plane coincident with that of the rear edge 26 of the anvil 25. The groove 28 provides a passageway for the edge of the cutting blade 7b on the one end of each pile wire which, as the pile wire is withdrawn from the fabric in a direction transversely thereof, cuts the wire crossing ends x of the loops X and any and all warp ends lying in the path of the blade across the groove 28, the complementary faces 26 and 29 firmly supporting the pile loops as the said loops are cut by the blade 7b during the withdrawal of the pile wire 7a from the fabric.

The plate 21 may be supported in any suitable manner and in the present instance is supported on the upper surface 19 of the breast plate 20 by a strip, bar, or a series of blocks 30 which are rigidly secured to the breast plate 2 and to the supplementary plate 21 in any suitable manner, as by screws or bolts.

As the fabric is moved forwardly, by the beat-up of the lay L and the take-up spiked roll above mentioned, the elements 11 will rock in the slot 24 from the wall 13 of the slot to the wall 23 of the slot by reason of the contact of the edge 15 of each element 11 with the pile warp threads.

Those of the pile warp threads which are still connected to the fabric will be pulled over the edges 15 of the elements 11, carrying with them any loose small pieces of yarn which have been severed from the fabric. On the back movement 5 of the lay L the elements 11 will be moved back into contact with the wall 13, due to the back tension on the warp threads, thus the edges 15 of the elements 11 act as ratchets to permit the warps which are still secured to the fabric and the pieces 10 of yarn which are not subjected to back tension to advance and at the same time keeping the pile warps which are subjected to the back tension from being pulled loose from the holding means and fall behind the flange 3 of the breast plate 2. 15

The small pieces of yarn are carried along the plate 21, and drop over the front edge thereof, by the advancing movement of the fabric and any small pieces of yarn which may fall into the groove 28 act as a pad for the blade 7b and prevent its scraping along the metal walls 26-29. The movement of the blades 7b always in the one direction through the groove 28 tends to keep the slot from becoming solidly packed with the small pieces of yarn which are cut into relatively fine 25 waste by the blades and dragged by the blades out of the one end of the groove.

I claim:

1. In a loom employing a series of warp threads arranged to be incorporated in, severed from, and held in a predetermined position relative to a fabric being woven and maintained tautly in said loom, stationary means engaged by the fabric with predetermined warps of said series positioned therebetween, and relatively movable 35 means operable perpendicular to said fabric and holding said threads in firm gripping contact with said fabric.

2. In a loom employing a series of warp threads arranged to be incorporated in, severed from, and held in a predetermined position relative to a fabric being woven and maintained tautly in said loom, stationary means engaged by the fabric with predetermined warps of said series positioned therebetween, and relatively movable 45 means operable perpendicular to said fabric and holding said threads in firm gripping contact with said fabric, and means yieldingly pressing said holding means into said gripping contact with said threads.

3. In a loom employing a series of warp threads arranged to be incorporated in, severed from, and held in a predetermined position relative to a fabric being woven and maintained tautly in said loom, means operable both perpendicular to said 55 fabric and with said fabric warpwise thereof and holding said threads in firm gripping contact with said fabric, means yieldingly pressing said holding means into said gripping contact with said threads, and means limiting the movement of said 60 holding means warpwise of the fabric.

4. In a loom employing a series of warp threads arranged to be incorporated in, severed from, and held in a predetermined position relative to a fabric being woven and maintained tautly in said loom, means operable both perpendicular 65 to said fabric and with said fabric warpwise thereof and holding said threads in firm gripping contact with said fabric, means yieldingly pressing said holding means into said gripping contact with said threads, means limiting the movement of said holding means warpwise of the fabric, and primary holding means pressing said threads into 70 gripping contact with said fabric adjacent and 75

parallel to said perpendicularly operable holding means.

5. In a loom employing a series of warp threads arranged to be incorporated in, severed from, and held in a predetermined position relative to a fabric being woven and maintained tautly in said loom, means operable both perpendicular to said fabric and with said fabric warpwise thereof and holding said threads in firm gripping contact with 10 said fabric, means yieldingly pressing said holding means into said gripping contact with said threads, means limiting the movement of said holding means warpwise of the fabric, primary holding means pressing said threads into gripping contact with said fabric at one side of and adjacent and parallel to said perpendicularly operable holding means, and means at the opposite side of and adjacent and parallel to said perpendicularly operable holding means supporting 15 said threads in position to be severed from said fabric.

6. In a loom employing a series of warp threads arranged to be incorporated in, severed from, and held in a predetermined position relative to a fabric being woven and maintained tautly in said loom, means operable both perpendicular to said fabric and with said fabric warpwise thereof and holding said threads in firm gripping contact with said fabric, means yieldingly pressing said holding means into said gripping contact with said threads, means limiting the movement of said holding means warpwise of the fabric, primary holding means pressing said threads into gripping contact with said fabric at one side of and adjacent and parallel to said perpendicularly operable holding means, means at the opposite side of and adjacent and parallel to said perpendicularly operable holding means supporting said threads in position to be severed from said fabric, 20 and means operable in a plane parallel to said supporting means and effecting said severing.

7. In a loom employing a series of warp threads arranged to be incorporated in, severed from, and held in a predetermined position relative to a fabric being woven and maintained tautly in said loom, means operable perpendicular to said fabric and comprising an element having a relatively sharp edge engaging and holding said threads in firm gripping contact with said fabric.

50 8. In a loom employing a series of warp threads arranged to be incorporated in, severed from, and held in a predetermined position relative to a fabric being woven and maintained tautly in said loom, means operable perpendicular to said fabric and comprising a series of relatively movable elements respectively provided with relatively sharp edges aligned transversely of the fabric and holding said threads in firm gripping contact with said fabric.

60 9. In a loom employing a series of warp threads arranged to be incorporated in, severed from, and held in a predetermined position relative to a fabric being woven and maintained tautly in said loom, means operable perpendicular to said fabric and comprising a series of relatively movable elements respectively provided with relatively sharp edges aligned transversely of the fabric and holding said threads in firm gripping contact with said fabric, and means yieldingly pressing said holding edges independently into said gripping contact with said threads.

70 10. In a loom employing a series of warp threads arranged to be incorporated in, severed from, and held in a predetermined position relative to a fabric being woven and maintained

tautly in said loom, means operable perpendicular to said fabric and comprising a series of relatively movable elements respectively provided with relatively sharp edges aligned transversely of the fabric and holding said threads in firm gripping contact with said fabric, and means yieldingly pressing said holding edges independently into said gripping contact with said threads, said elements being operable in a slot having a width greater than the thickness of said elements and affording predetermined movement of said elements with said fabric in a direction warpwise of said fabric.

11. In a loom employing a series of warp threads arranged to be incorporated in, severed from, and held in a predetermined position relative to a fabric being woven and maintained tautly in said loom, means operable perpendicular to said fabric and comprising a series of relatively movable elements respectively provided with relatively sharp edges aligned transversely of the fabric and holding said threads in firm gripping contact with said fabric, means yieldingly pressing said holding edges independently into said gripping contact with said threads, said elements being operable in a slot having a width greater than the thickness of said elements and affording predetermined movement of said elements with said fabric in a direction warpwise of said fabric, and a stationary element having a 20 thread-engaging edge parallel to and adjacent one side of said slot exerting an initial holding pressure on said threads.

12. In a loom employing a series of warp threads arranged to be incorporated in, severed from, and held in a predetermined position relative to a fabric being woven and maintained tautly in said loom, means operable perpendicular to said fabric and comprising a series of relatively movable elements respectively provided with relatively sharp edges aligned transversely of the fabric and holding said threads in firm gripping contact with said fabric, means yieldingly pressing said holding edges independently into said gripping contact with said threads, said elements being operable in a slot having a width greater than the thickness of said elements and affording predetermined movement of said elements with said fabric in a direction warpwise of said fabric, and a blade operable in a direction 30 parallel to and at the opposite side of said slot for severing said threads from said fabric.

13. In a loom employing a series of warp threads arranged to be incorporated in, severed from, and held in a predetermined position relative to a fabric being woven and maintained tautly in said loom, a fabric-supporting element having a beveled edge over which said fabric and said threads pass and which by reason of the tautness of said fabric presses said threads into firm-gripping contact with said fabric.

14. In a loom employing a series of warp threads arranged to be incorporated in, severed from, and held in a predetermined position relative to a fabric being woven and maintained tautly in said loom, a pair of substantially parallel laterally spaced beveled edges over which said fabric and said threads pass in superposed relation to each other with said threads pressed into firm-gripping contact with said fabric at substantially parallel transversely extending planes spaced warpwise of the fabric by said beveled edges respectively.

15. In a loom employing a series of warp threads arranged to be incorporated in, severed

from, and held in a predetermined position relative to a fabric being woven and maintained tautly in said loom, a pair of substantially parallel laterally spaced beveled edges over which said fabric and said threads pass in superposed relation to each other with said threads pressed into firm-gripping contact with said fabric at substantially parallel transversely extending planes spaced warpwise of the fabric by said beveled edges respectively, means affording stationary support for one of said edges, and means affording yielding support for the second of said edges.

16. In a loom employing a series of warp threads arranged to be incorporated in, severed from, and held in a predetermined position relative to a fabric being woven and maintained tautly in said loom, a pair of substantially parallel laterally spaced beveled edges over which said fabric and said threads pass in superposed relation to each other with said threads pressed into firm-gripping contact with said fabric at substantially parallel transversely extending planes spaced warpwise of the fabric by said beveled edges respectively, one of said edges being composed of a series of substantially aligned sections relatively movable with respect to each other and to the second of said pair of edges.

17. In a loom employing a series of warp threads arranged to be incorporated in, severed from, and held in a predetermined position relative to a fabric being woven and maintained tautly in said loom, a pair of substantially parallel laterally spaced beveled edges over which said fabric and said threads pass in superposed relation to each other with said threads pressed into firm-gripping contact with said fabric at substantially parallel transversely extending planes spaced warpwise of the fabric by said beveled edges respectively, one of said edges being composed of a series of substantially aligned sections relatively movable with respect to each other and to the second of said pair of edges for independent movement in a plane parallel to that of said second edge and in a direction at right angles to said plane.

18. In a loom weaving fabric including parallel courses of pile loops formed respectively over transversely extending wires, a support for and extending transversely of the fabric, and an anvil spaced from and extending parallel to said support and adapted to be engaged by and to support said courses successively in a predetermined loop-cutting position.

55 19. In a loom weaving fabric including parallel courses of pile loops formed respectively over transversely extending wires, an anvil having an inclined pile course engaging surface disposed at an angle substantially coinciding with the natural angle of inclination of the foremost of said courses of pile loops arranged to be engaged by and to support said courses successively in a predetermined loop-cutting position.

65 20. In a loom weaving fabric including parallel courses of pile loops formed respectively over transversely extending wires, an anvil having an inclined pile course engaging surface disposed at an angle substantially coinciding with the natural angle of inclination of the foremost of said courses of pile loops arranged to be engaged by and to support said courses successively in a predetermined loop-cutting position, and a cutting blade on one end of each wire operable in a plane substantially paralleling said inclined surface for

cutting said loops as said wires are successively withdrawn from the fabric.

21. In a loom weaving fabric including parallel courses of pile loops formed respectively over transversely extending wires, an anvil having an inclined pile course engaging surface disposed at an angle substantially coinciding with the natural angle of inclination of the foremost of said courses of pile loops arranged to be engaged by and to support said courses successively in a predetermined loop-cutting position, a cutting blade on one end of each wire operable in a plane substantially paralleling said inclined surface for cutting said loops as said wires are successively withdrawn from the fabric, and a support for said anvil projecting rearwardly from said inclined surface of said anvil and provided with a groove in which said blade operates.

22. In a loom weaving pile fabric with pile warps held against said fabric, to be tied into said fabric, to be formed into successive courses of pile loops around wires extending transversely of said fabric, and to be severed from said fabric, the combination of a horizontally disposed breast plate, a vertical flange on the breast plate over the upper edge of which said fabric and said warp threads pass and pressing said threads into gripping contact with one of said courses of pile loops which overlies the upper edge of the flange, a supplementary plate on said breast plate with the rear edge of the supplementary plate spaced from and parallel to the front face of said flange providing a slot therebetween, a blade operable in the slot perpendicular to said fabric, and means raising the blade in the slot until the upper edge of the blade engages and presses said threads into firm gripping contact with said fabric on a line paralleling said upper thread-gripping edge of said flange.

23. In a loom weaving pile fabric with pile warps held against said fabric, to be tied into said fabric, to be formed into successive courses of pile loops around wires extending transversely of said fabric, and to be severed from said fabric, the combination of a horizontally disposed breast plate, a vertical flange on the breast plate over the upper edge of which said fabric and said warp threads pass and pressing said threads into gripping contact with one of said courses of pile loops which overlies the upper edge of the flange, a supplementary plate on said breast plate with the rear edge of the supplementary plate spaced from and parallel to the front face of said flange providing a slot therebetween, a series of relatively movable blade sections having upper edges longitudinally aligned transversely of said fabric and operable in said slot perpendicular to the fabric, and a series of springs respectively raising said blade sections independently until said upper edges thereof engage and press said threads into gripping contact with a course of said pile loops disposed in spaced parallel relation to said course overlying said flange.

24. In a loom weaving pile fabric with pile warps held against said fabric, to be tied into said fabric, to be formed into successive courses of pile loops around wires extending transversely of said fabric, and to be severed from said fabric, the combination of a horizontally disposed breast plate, a vertical flange on the breast plate over the upper edge of which said fabric and said warp threads pass and pressing said threads into gripping contact with one of said courses of pile loops which overlies the upper edge of the flange, a supplementary plate on said breast plate with

the rear edge of the supplementary plate spaced from and parallel to the front face of said flange providing a slot therebetween, a blade operable in the slot perpendicular to said fabric, means 5 raising the blade in the slot until the upper edge of the blade engages and presses said threads into firm gripping contact with said fabric on a line paralleling said upper thread-gripping edge of said flange, an anvil on one of said plates forward of said slot and having a rear surface engaged by said courses of pile loops successively to hold the foremost of said courses in predetermined loop-cutting position parallel to said slot, and a cutting blade operable intermediate said 10 slot and said anvil for cutting said foremost course of loops.

25. In a loom weaving pile fabric with pile warps held against said fabric, to be tied into said fabric, to be formed into successive courses 20 of pile loops around wires extending transversely of said fabric, and to be severed from said fabric, the combination of a horizontally disposed breast plate, a vertical flange on the breast plate over the upper edge of which said fabric and said 25 warp threads pass and pressing said threads into gripping contact with one of said courses of pile loops which overlies the upper edge of the flange, a supplementary plate on said breast plate with the rear edge of the supplementary plate spaced 30 from and parallel to the front face of said flange providing a slot therebetween, a blade operable in the slot perpendicular to said fabric, means raising the blade in the slot until the upper edge of the blade engages and presses said threads 35 into firm gripping contact with said fabric on a line paralleling said upper thread-gripping edge of said flange, an anvil on one of said plates forward of said slot and having a rear surface engaged by said courses of pile loops successively 40 to hold the foremost of said courses in predetermined loop-cutting position parallel to said slot, and a cutting blade operable in and longitudinal of a groove formed in one of said plates intermediate said slot and said anvil for cutting 45 said foremost course of loops.

26. In a loom weaving pile fabric with pile warps held against said fabric, to be tied into said fabric, to be formed into successive courses 50 of pile loops around wires extending transversely of said fabric, and to be severed from said fabric, the combination of a horizontally disposed breast plate, a vertical flange on the breast plate over the upper edge of which said fabric and said 55 warp threads pass and pressing said threads into gripping contact with one of said courses of pile loops which overlies the upper edge of the flange,

a supplementary plate on said breast plate with the rear edge of the supplementary plate spaced from and parallel to the front face of said flange providing a slot therebetween, a blade operable in the slot perpendicular to said fabric, means 5 raising the blade in the slot until the upper edge of the blade engages and presses said threads into firm gripping contact with said fabric on a line paralleling said upper thread-gripping edge of said flange, an anvil on one of said plates 10 forward of said slot and having a rear surface engaged by said courses of pile loops successively to hold the foremost of said courses in predetermined loop-cutting position parallel to said slot, and a cutting blade operable in and longitudinal of a groove formed in one of said plates 15 intermediate said slot and said anvil for cutting said foremost course of loops, said rear surface of said anvil and a corresponding surface of said groove being contiguously disposed in a common plane. 20

27. In a loom weaving pile fabric with pile warps held against said fabric, to be tied into said fabric, to be formed into successive courses 25 of pile loops around wires extending transversely of said fabric, and to be severed from said fabric, the combination of a horizontally disposed breast plate, a vertical flange on the breast plate over the upper edge of which said fabric and said 30 warp threads pass and pressing said threads into gripping contact with one of said courses of pile loops which overlies the upper edge of the flange, a supplementary plate on said breast plate with the rear edge of the supplementary plate spaced from and parallel to the front face 35 of said flange providing a slot therebetween, a blade operable in the slot perpendicular to said fabric, means raising the blade in the slot until the upper edge of the blade engages and presses said threads into firm gripping contact with said 40 fabric on a line paralleling said upper thread-gripping edge of said flange, an anvil on one of said plates forward of said slot and having a rear surface engaged by said courses of pile loops successively to hold the foremost of said courses 45 in predetermined loop-cutting position parallel to said slot, and a cutting blade operable in and longitudinal of a groove formed in one of said plates intermediate said slot and said anvil for cutting 50 said foremost course of loops, said rear surface of said anvil and a corresponding surface of said groove being contiguously disposed in a common plane inclined forwardly in accordance with the natural inclination of the foremost course of uncut loops. 55
